UNITED STATES PATENT OFFICE.

JOHN J. DOLL, OF NEW YORK, N. Y.

MUSICAL INSTRUMENT.

1,299,146.

Specification of Letters Patent.

Patented Apr. 1, 1919.

Application filed April 1, 1913. Serial No. 758,147.

To all whom it may concern:

Be it known that I, JOHN J. DOLL, a citizen of the United States, residing at the borough of Manhattan, in the county of New York and State of New York, have invented certain new and useful Improvements in Musical Instruments, of which the following is a specification, reference being had therein to the accompanying drawing.

- 10 My invention relates to improvements in the operating mechanism for the music spools for player pianos, and has particular reference to means in combination with the take-up spool whereby the speed of the same is gradually decreased as the perforated music sheet is wound thereupon so as to maintain constant the speed of movement of the perforated sheet with reference to the tracker bar.
- 15 Referring to the accompanying drawings, I have illustrated in Figure 1 in front elevation, the pneumatic motor and the music spools and connections for operating the same. Fig. 2 is a view looking from right to left at Fig. 1, and Fig. 3 is an enlarged perspective view showing part of the automatic regulating mechanism by which the speed of the take-up roll is gradually decreased as the perforated sheet is wound thereupon.

4 indicates the music spool from which the perforated sheet is wound upon the spool 5. 6 indicates the gear upon the end of the spool 5 adapted to be engaged by the pinion 7 upon the shaft 8 which is adapted to be rotated by the sprocket 9, carrying the chain 10, which also passes over the sprocket 11 upon the shaft 12 of the loaded spool 4. 13 indicates another sprocket upon the shaft 8 provided with the sprocket chain 14 which also passes over the sprocket 15 upon the crank shaft 16 of the pneumatic motor 17. From this it will be seen that when the pneumatic motor 17 is in operation power is transmitted through the crank shaft 16, sprocket 15, chain 14, sprocket 13, and shaft 8 into the sprocket 9 which rotates freely with the shaft 8 carrying the pinion 7 until the coupling 19 is thrown leftwardly by the levers 20—21 connected to the pneumatic 22 which is under the control of the operator. When the coupling 19 is thrown leftwardly, it shifts the shaft 8 and its pinion 7 leftwardly until said pinion engages the gear 6 thereby causing the take-up spool to revolve. As the

said spool revolves winding upon itself the perforated sheet 18, the diameter of the same increases, causing the roller 22 upon the bar 23 which said roller rides upon the surface of the same as shown, to rotate the said bar 23 upon its bearing 23', lifting the crank 24 thereof, having the extension arm 25 suitably connected to the rod 26, attached to the slide 27 thereby raising the said slide gradually as the music is wound upon the said take-up roll 5.

The flow of air controlling the pneumatic motor 17 is controlled through the passage 28 which in turn is controlled by the slide 27 so that as the slide 27 is raised the speed of the pneumatic motor 17 is gradually decreased and the speed of revolution of the music roll 5 is proportionately decreased with the increase in its diameter, thus insuring a constant speed of travel of the said perforated music sheet across the said tracker bar 29.

When it is desired to rewind the perforated sheet 18 upon the roll 4 it is only necessary for the operator to again operate the pneumatic 22 so that the lever 21 is thrown leftwardly, thereby causing the connecting lever 20 and coupling 19 to disconnect the pinion 7 from the gear 6 and allowing said coupling 19 to become engaged with the sprocket wheel 9 by which the power is transmitted to the sprocket wheel 11 by the chain 10, thus causing the music roll 4 to rewind upon itself the said perforated sheet 18.

The spring 31 attached to the casing 32 within which the slide 27 is mounted is connected at its other extremity to the crank 24 of the bar 23 thereby maintaining the roller 22 with slight tension always upon the face of the perforated roll of music, so that it will be seen that as the perforated sheet is wound back on to the roll 4 from the roll 5, the automatic control roller 22 will follow back to its original position upon the core of the take-up spool 5.

33 is a valve pivoted by the pin 34 at the back of the casing 32 adapted to rest against the end of the screw 35, passing through the hole of the casing and being maintained in said position by suitable resilient means such as the spring 36. From this it will be seen that as the screw 35 is turned, the amount of the opening 28 may be reduced or enlarged as may be found preferable. It will also be observed that the ends of the opening 28 are

V-shaped except that they are preferably curved as shown as it has been found that the best results are obtained by this form of opening.

5 Of course it will be understood that various modifications may be made without departing from the spirit of the invention as claimed.

I claim:

10 In an apparatus of the class described, a music spool and a take-up roll, a pneumatic motor and transmission therebtween, an air duct supplying air to said motor and a valve

in said air duct, a U-shaped bar having one leg connected to said valve and the other 15 leg provided with a roller adapted to bear upon the face of said take-up roll whereby as said take-up roll fills, said valve reduces the supply of air to said motor.

15 In testimony whereof I affix my signature 20 in presence of two witnesses.

JOHN J. DOLL.

Witnesses:

LOUISE ENDERLE,
THOMAS A. HILL.
